UNITED STATES PATENT OFFICE.

LEE LA TOUR AND ALTON F. MUNNELL, OF OMAHA, NEBRASKA, ASSIGNEES, BY
DIRECT AND MESNE ASSIGNMENTS, TO PROGRESS ROLLER COMPANY, OF
OMAHA, NEBRASKA, A CORPORATION.

DESIGN FOR AN INKING-ROLLER.

59,017.

Specification for Design.

Patented Sept. 13, 1921.

Application filed December 22, 1919. Serial No. 346,797. Term of patent 14 years.

To all whom it may concern:

Be it known that we, LEE LA TOUR and ALTON F. MUNNELL, citizens of the United States, residing at Omaha, in the county of Douglas and State of Nebraska, have invented a new, original, and ornamental Design for an Inking-Roller, of which the following is a specification, reference being had to the accompanying drawing, forming a part thereof.

Figure 1 is a side or plan view of an inking roller, showing our new design. Fig. 2 is an end view of the same.

We claim:

The ornamental design for an inking roller, as shown.

In testimony whereof, we have affixed our signatures in presence of two witnesses.

LEE LA TOUR.
ALTON F. MUNNELL.

Witnesses:

HIRAM A. STURGES,
ARTHUR H. STURGES.
